GRINDER FOR PIGMENTS AND OTHER MATERIALS

Harding F. Bakewell, San Marino, Calif.

Application May 22, 1948, Serial No. 28,607

5 Claims. (Cl. 241—215)

1

The present invention relates generally to grinders or mills, and is more particularly concerned with grinders of the type which are adapted to the fine grinding of pigments and other similar materials. However it will be understood that the material ground in the device constitutes no limitation upon my invention, since the constructions and principles of operation described herein may be readily adapted to grinders for many different kinds of materials.

Grinders of the type with which we are here concerned generally comprise a pair of cooperating grinding elements, of which one is stationary and the other rotates. These elements are typically Carborundum stones and so are referred to herein as "stones," but other substances may be used for one or both of the grinding or crushing elements, as may be best adapted to the material being ground. In general, devices of this character have one stone which rotates about a fixed axis with respect to the other stone, the material being ground passing outwardly between the two stones so that there normally exists a thin film of the pigment or other material between the two stones.

However, there occur times in grinding when the supply to the grinder is interrupted, or for some other reason the film of pigment or other material between the stones fails or becomes discontinuous. Under these conditions, it has happened that the grinding elements come into contact with each other and, being very abrasive, they rapidly score each other. At times, the grinding elements so deeply abrade each other that they are entirely ruined before the grinder can be stopped or the film of pigment restored, so that the grinding elements must be at least refaced and in some instances replaced.

Even if the film of pigment or the like is maintained, the two grinding elements may tend to abrade one another. If a high spot develops on one stone, it wears a groove in the other, with the result that the coating grinding surfaces on the two stones often become scored. This situation results from the condition that any point on one stone continuously retraces the same path on the other stone.

Another difficulty encountered with known types of grinders is that of establishing proper separation or spacing between the grinding elements in order to control the size of the ground product. In order to produce a closely sized product, it is necessary that this spacing be established with certainty and within narrow limits, and also that it be quickly and easily adjustable

2

and capable of being maintained. Otherwise, the product may be of other than expected size.

In conventional grinders of this general type, considerable difficulty has been experienced in obtaining proper dynamic balance of the rotor assembly. As a result, the main bearings are subjected to relatively high impact loadings as the out-of-balance grinding element is rotated at high speed, and these bearings frequently fail and need replacement. It is impractical to obtain perfect dynamic balance of the rotating stone; and in any event wear is frequently uneven so that the stone becomes unbalanced in use.

Thus it becomes a general object of my invention to provide a grinding device of the character described in which the relatively movable grinding element has a motion such that one particle on the moving stone does not continuously retrace the same path on the stationary stone, but rather follows a variable path so that the coating surfaces are maintained in the best possible condition for grinding.

It is also a primary object of my invention to provide a grinding device of the character described in which the motion of the grinding elements aids in crushing the pigment or other material being ground and feeding it past the grinding surfaces in order to maintain a continuous film of pigment between the grinding surfaces.

It is a further object of my invention to provide a grinding device having means for initially establishing and maintaining the proper spacing between the grinding elements in order that the size of the product can be closely established and maintained.

It is also an object of my invention to provide a grinder in which the bearings are protected against shocks resulting from rotation of an unbalanced grinding element.

The above and other objects of my invention are attained by providing a grinding device having a pair of cooperating grinding elements of which one is stationary and the other is rotatable, and means for mounting the rotatable element in such fashion that it has a movement which may be described as being an oscillatory rotational movement. In the preferred embodiment of my invention described herein, the two grinding elements have spherically contoured coating surfaces, and the shaft carrying the rotating element is resiliently or flexibly mounted at or near one end so that its longitudinal axis, which is the axis of rotation of the shaft and the stone, can be deflected and caused to move over a predetermined definite path. Thus, in addition to the

strict rotational movement, the stone has imparted to it a second motion which causes the stone, when viewed from one side to appear to oscillate across the stationary stone. The resultant motion is thus a compound rotational and oscillatory motion which produces a novel radial component to the relative motion of the two elements in addition to the normal circumferential component.

The stationary stone is mounted for closely controlled limited movement toward and away from the moving stone, this motion being obtained by providing two threadedly interengaging members one of which is held against rotation and the other of which is held against movement of translation, so that rotation of the latter moves the former toward or away from the rotating grinding element. These two members are enclosed in a fluid-tight chamber so that fluid pressure can be applied to the end of the translatable member to establish a predetermined grinding pressure at the coacting grinding surfaces.

How the above objects and advantages of my invention, as well as others not specifically referred to herein, are attained will be more readily understood by reference to the following description and to the annexed drawings, in which:

Fig. 1 is a vertical median section through a grinding device constructed according to my invention;

Fig. 2 is a plan view as indicated by line 2—2 in Fig. 1;

Fig. 3 is a horizontal transverse section taken on line 3—3 of Fig. 1 showing the eccentric mounting for the upper shaft bearing;

Fig. 4 is a plan view of the rotatable grinding element removed from the remainder of the device;

Fig. 5 is a fragmentary vertical transverse section similar to Fig. 1 showing a modified form of grinding elements; and

Fig. 6 is a horizontal transverse section on line 6—6 of Fig. 1 showing a planetary gear train used to obtain the eccentric motion of the rotating shaft.

Referring now to the drawings, it will be seen that the grinder is enclosed in a housing which is generally upwardly extending and is circular in cross section, or approximately so. I prefer that the rotor assembly turn about a vertical axis as shown and later described; but my invention is not necessarily so limited as an inclined or horizontally extending axis may be used if desired. This housing comprises a head section 10 which is pivotally mounted at 11 onto the next lower section 12 which forms the enclosure for the grinding chamber 15. A discharge spout 14 is located at one side of the housing for removal of the ground products from grinding chamber 15. The bottom section 16 of the housing provides a pedestal or stand for the device and also encloses the driving mechanism, drive motor 17 being enclosed in section 16a of the housing.

The grinding means is located within grinding chamber 15 and comprises a pair of cooperating, relatively movable grinding elements. The upper element 20 is stationary while the lower element 21 is mounted for a compound rotational motion as will be described. The two grinding elements are usually stones, either natural or artificial, but may equally well be metal or other substances which are suited to the type of grinding and the kind of material being handled by the device.

Both grinding elements 20 and 21 are annular

in configuration, and define an annular grinding zone at the coacting annular grinding surfaces of the two elements indicated at 23. Grinding surfaces 23 are spherically contoured, as will be explained more fully. The lower stone 21 is mounted upon back plate 22 which is preferably lightened by providing openings 22a inwardly of the position of the stone. The grinding element is held in place by disc 24 which engages a lip or projecting rim on the stone and is secured by nut 25 to the upper end of drive shaft 27.

Drive shaft 27 is journaled at a point intermediate its ends, and preferably just below the hub of plate 22, in bearing 29 to rotate about its longitudinal axis 28. This bearing may be of any suitable type but is here shown as being a ball bearing of which the outer race is held in a composite steel-and-rubber bushing indicated generally at 30. A layer of steel in this bushing is next to the outer race of bearing 29 and is bonded to a surrounding rubber layer which in turn is bonded to an outer steel shell.

Bushing 29 fits within a circular bore 31 open to the upper end of sleeve 33. Sleeve 33 is journaled at its upper end in ball bearing 34 and its lower end in a similar bearing 35 so that it is free to revolve about axis 36 with respect to intermediate housing section 12 which encloses and supports bearings 34 and 35. Bore 31 is eccentric with respect to the axis 36 of revolution of sleeve 33, as may be seen in Figs. 1 and 3, the bore being offset to the left of axis 36 in Fig. 1. Cover plate 38 is bolted to the upper end of sleeve 33 to rotate therewith, and holds bushing 30 in place in bore 31. Cover 38 fits over the stationary parts of housing 12 with small clearance in order to protect the bearings to a greater or less extent against the entry of material from grinding chamber 15.

At the lower end of drive shaft 27, there is located driving pulley 40 which is rotatably mounted in two spaced bearings indicated at 41 so that the pulley turns freely within housing section 16 about axis 36. Centrally located within pulley 40 is a thrust bearing block 42 which receives the end thrust on shaft 27. The lower end of drive shaft 27 is rounded at 43 in the shape of a hemisphere with its center at 44, as shown in Fig. 1, and this lower end of the shaft, which is opposite to the end carrying stone 21, is seated in thrust bearing 42. Because of the hemispherical shapes of the end of the shaft and the co-operating seat in the thrust bearing, shaft 27 is able to rock slightly in the bearing and yet the vertically applied loads do not change in their point of application so that the reaction forces in the bearing do not shift substantially in position or direction. Center 44 is located on the longitudinal axis 28 of shaft 27 and is also the center of the spherical grinding surfaces 23, permitting these surfaces to move relative to each other when stone 21 swings about center 44, without disengaging the grinding surfaces. Since center point 44 lies on both axes 28 and 36, these two axes intersect at 44.

Drive shaft 27 is drivingly connected to pulley 40 by a flexible connection indicated generally at 45, which may be another composite steel-and-rubber member that allows shaft 27 to rock slightly in seat 43 yet continues to deliver driving torque to the shaft. Connection 45 comprises an inner cylindrical metal sleeve fastened to drive shaft 27 by splines 47 and also connected to the surrounding flexible or elastic portion 45a which fits within bore 46 opening at the top side of

drive pulley 40. Bore 46 is concentric with pulley 40 and axis 36.

Drive pulley 40 is driven by a plurality of V-belts 48 which pass over a pulley 49 on the end of the shaft of motor 17.

Sleeve 33 is driven from drive pulley 40 by means of a planetary gear train which is shown in both Figs. 1 and 6. This gear train comprises an internal ring gear 51 attached to the bottom edge of sleeve 33, and a similar internal ring gear 52 which is fastened to the walls of housing section 12 and so is stationary. Ring gears 51 and 52 are of slightly different diameters in order that one ring gear revolves with respect to the other and so drives sleeve 33. This difference in diameters may be varied according to the relative speeds which are desired; but the rotational speed of sleeve 33 need not be very high. Ring gear 52, which is the lower one, is here shown as being of larger diameter. Inside the two ring gears, is a plurality of pinions, as seen best in Fig. 6. The upper pinions 54 mesh with ring gear 51, while the lower pinions 55 mesh with the other ring gear 52. The pinion gears are arranged in pairs of an upper and a lower gear which are drivingly connected by a sleeve 56 journaled on a vertically extending pin 57. There are three such pairs of pinions, although the number may be increased or decreased as desired, and a corresponding number of pins 57. The lower ends of pins 57 are held in sockets in plate 58 which is fastened to the upper end of pulley 40. Plate 58 also serves to close bore 46 and hold bushing 45 securely in place. The upper ends of pins 57 are held in position by ring 59.

It will be noted that lower pinions 55 are of larger diameter than upper pinions 54 in order properly to mesh with the larger ring gear 52.

Going now to the upper end of the grinder, it will be noted that stationary grinding element 20 is mounted upon the lower end of an annular carrier member 65 which is mounted for sliding movement within head 10 of the housing. Member 65 is held against rotation within the housing by key 63 in keyway 64 so that the only movement of which the carrier is capable is one of translation toward and away from the lower grinding element 21. Keyway 64 is preferably parallel to axis 36; and translation of member 65 then moves the upper grinding element also toward and away from the lower rotatable grinding element. Carrier member 65 threadedly engages at 66 sleeve 67 which surrounds and is journaled upon an inner fixed sleeve 68 which is fastened at its upper end to housing section 10. The threads at 66 are preferably a loose fit, having a predetermined clearance of a few thousandths of an inch, for reasons explained later. Sleeve 68 provides an inlet passage for the feed to the grinding chamber and is arranged concentrically with the upper annular grinding element 20.

Sleeve 67 is confined at both ends against axial movement on inner sleeve 68, so that the outer sleeve 67 is capable only of rotational movement. This rotational movement is imparted by pinion 70 which meshes with gear 71 which may very conveniently be made as an integral portion of the upper end of sleeve 67. Pinion 70 is mounted on the lower end of shaft 72 which is journaled in housing 73a mounted on the upper end of head section 10. Shaft 72 is turned by handle 75 at the upper end of the shaft. Thus rotation of handle 75 effects corresponding rotational movement of shaft 72 and gear 70 which produces a smaller

rotational movement of sleeve 67. By virtue of the threaded interengagement at 66 between sleeve 67 and carrier 65 and key 63 engaging the wall of the housing, such rotation of sleeve 67 produces linear movement of stationary stone 20 and its carrier 65.

Handle 75 is preferably adjustable relative to shaft 72, and it is also desirable to provide some type of detent mechanism to hold the handle and shaft in selected rotational positions. To obtain adjusting movement of the handle, it is journaled at its inner end on shaft 72, as shown in Fig. 1. The handle carries on its upper side a slide 74 which can be moved longitudinally of the handle. Slide 74 carries at its inner end a driving dog 74a which, when the slide is advanced inwardly toward shaft 72, engages the teeth of cog-wheel 73, in the manner shown in Fig. 2. Cog-wheel 73 is mounted on the squared upper end of shaft 72 so that rotation of the cog-wheel rotates the pinion shaft. Cog-wheel 73 is held in place by lock nut 78 on the end of shaft 72 which is covered by cover plate 79.

In order to hold handle 75 in any selected rotational position, there is provided a detent plate 76 which has a number of radially extending depressions or notches 76a in its upper surface. A small projection 75a on the under side of handle 75 is adapted to drop into any one of these radial depressions 76a to hold the handle frictionally in that position.

I prefer that the depressions 76a be so spaced angularly, and the gear ratio between pinion 70 and the driven gear 71 be so calculated, that the angular movement of handle 75 required to advance the handle from one depression 76a to the next one results in a known and predetermined movement of grinding element 20. It is convenient if this movement of the handle moves the grinding element by either .001" or .0005" for each notch in the detent plate, and the detent plate is marked accordingly; but of course it will be understood that the plate may be graduated in any other convenient unit of movement, as may be desired. Depressions 76a may be numbered, with zero at one end of plate 76, or other indexing means may be used, if desired, in order to indicate the movement of stationary element 20 obtained by any given rotation of handle 75.

The upper portion of the interior of housing 10 is designed to be a fluid-tight chamber, so that when fluid under pressure is admitted through inlet pipe 80 the upper radial surface of carrier member 65 has fluid pressure applied to it and the member acts as a piston in a cylinder. Line 81 is preferably provided with an air chamber 81 as indicated for reasons to be mentioned later; but such chamber is optional. In order to hold this fluid pressure, members 67 and 65 may be provided with O-rings or other sealing means as indicated. Additional sealing members may be used as required to hold adequately the applied fluid pressure. It will be noted that this fluid pressure does not interfere with the rotational movement of sleeve 67 but that it effects axial movement of the translatable member 65.

The assembly of parts for mounting and adjustably positioning the upper grinding element 20 are carried inside head section 10 which is pivotally connected at 11 to the intermediate housing section 12. In order that housing sections 10 and 12 are kept in tight engagement to close the upper end of grinding chamber 15,

latch means is provided on housing section 12 at a point opposite pivot 11. This latch means comprises plug 82 having on its under side an inclined cam surface which engages a similarly inclined surface on the upper face of lug 83 on housing section 10. Plug 82 has a stem 84 which is threadedly engaged by an internal thread in hand screw 85 so that stem 84 and plug 82 are advanced or retracted by manually rotating screw 85. As the plug 82 is advanced, it engages the upper surface on lug 83 and presses head section 10 downwardly into tight engagement with the opening into the grinding chamber within intermediate section 12.

The shape of the grinding elements is shown in Figs. 1 and 4. The upper grinding element 20 is an annulus gripped at its upper end for support and having at its lower end a spherically contoured grinding surface. The lower grinding element 21 is also generally annular in shape and is provided at its lower end with a lip which is engaged by disc 24 to hold the stone securely against back plate 22. The upper face of this stone is also spherically contoured to establish a grinding face which coacts with the similarly shaped face of upper stone 20. As shown in both Figs. 1 and 4, I preferably provide on the lower grinding element a plurality of pockets 21a in the inner face of the annular wall of the grinding element. These pockets are open to the spherical grinding surfaces and are located to receive the material to be ground from the feed zone at the center of the stones. The pockets taper down outwardly and crush any large pieces of pigment before feeding the pigment to the grinding zone. The pockets improve the continuity of feed of material to the grinding zone and so reduce the possibility of a discontinuity in the pigment film between the stones.

I prefer to place pockets 21a on the rotating element since in this way the centrifugal force of the rotating element is most effective to throw material into the pockets and feed it out of the pockets into the space between the two grinding surfaces at 23. However, as an alternate construction, I show in Fig. 5 a pair of modified grinding elements 87 and 88. The elements 87 and 88 correspond in general shape and function to the grinding elements 20 and 21 respectively shown in Fig. 1, except that pockets have been omitted in the rotating member and there has been substituted therefor a plurality of pockets 87a in the inner cylindrical wall of the stationary grinding element. These pockets also operate to collect and feed material to be ground to the grinding zone, but are located in the other grinding element than in the first embodiment of my invention. It is anticipated that under some circumstances this variational form may be preferred.

Bearing in mind the foregoing description of the construction of a grinding machine according to my invention, I shall now describe the operation thereof. Material to be ground is supplied to the grinder through an inlet 90 which communicates with the upper end of sleeve 68, as shown in Fig. 1. Inlet duct 90 may be a part of any suitable container or conveyor duct. Since the construction of this member is no essential part of the present invention, it is not shown in detail but it will be understood that the duct is so constructed by means not shown in the drawings, that it is movable for connection and disconnection to the upper end of sleeve 68. This is done since duct 90 must be removed before head

section 10 can be swung about pivot 11. The material to be ground may be fed to the grinder either as a wet slurry or in a dry granular state. In either condition, the material is fed by gravity at a rate suitable for the grinding capacity of this machine.

The initial step in using the machine is to adjust the spacing between the spherical grinding surfaces of elements 20 and 21 to produce the desired particle size. This is accomplished by first applying sufficient fluid pressure through conduit 80 to the upper face of member 65 to cause the latter to move slightly downwardly relative to sleeve 67. This takes up all the clearance between the threads at 66 so that no further relative translational movement takes place between members 65 and 67.

Next, sleeve 67 is rotated by means of handle 75 and pinion 70 until the upper grinding element is in contact with the lower grinding element. During this time, fluid pressure is maintained on the upper side of member 65. Now then an exact spacing between the grinding surfaces is obtained by reversing the direction of movement of handle 75 to back off the upper grinding element by the desired amount.

If the handle 75 has not already been zeroed, this step is taken at the time that the grinding elements are first brought into contact. It is done by moving slide 74 radially outward to disengage dog 74a from the teeth of cog-wheel 73. The handle, now free to turn about shaft 72, is brought to the zero marking on depressions 76a on the detent plate. Then slide 74 is advanced to re-engage cog-wheel 73. Now, rotation of handle 75 through a given arc separates stones 20 and 21 by the amount shown by the graduations on plate 76. The slide is locked in advanced position by tightening down screw 77.

All of this time, an adequate fluid pressure has been maintained on the upper end of member 65 to take up all clearance in the threads at 66 and cause the two members 65 and 67 to move as a unit toward or away from the rotating grinding element. Now that the proper grinding spacing has been established, a higher fluid pressure may be applied to conduit 80 as may be required in order to carry out the grinding operation. If relatively large particles of the material being ground lodge in between the two grinding elements and the inter-face pressure exceeds the fluid pressure, the upper stone can move upwardly away from the rotating element against the applied fluid pressure because the air chamber at 81 makes the fluid "elastic." Air chamber 81 acts as a pressure regulator and can be replaced by a conventional pressure relief valve, but has the advantage that it does not bleed fluid out of the system. This upward movement of the upper stone is limited by the amount of clearance in thread 66, and is against the fluid pressure above member 65 which continually tends to restore and maintain the initial spacing of the grinding elements. However, should the feed of pigment to the grinding zone fail for any cause for a sufficient length of time to break the continuity of the film of pigment between the grinding surfaces, the two stones are kept from dropping into contact with each other by mutual engagement of the threads at 66. Thus the stones may revolve in a dry condition, that is without any pigment between them, without harmful effects since the predetermined spacing between them cannot be decreased by failure of the pigment film. This construction permits applica-

tion of a given grinding pressure to the grinding elements yet insures that the clearance between them cannot drop below an established minimum.

The fluid pressure and the thread clearance can be omitted if desired. With a tight thread the spacing between stones is relatively constant and grinding pressure is applied through the threads at 66 rather than by fluid pressure on carrier member 65. Spacing may be established as described.

After the grinding spacing has been established, but before feed of material to the grinder is commenced, the lower grinding element is placed in motion by starting up motor 17. Motor 17 drives pulley 49 which, through the agency of belts 48, drives pulley 40. Shaft 27 being drivingly connected to pulley 40 through the agency of splines 47 and the flexible connection 45. The shaft turns with the pulley at the same speed and rotates the lower grinding element 21.

If bearing 29 were concentric with the axis 36 of revolution of drive pulley 40, then the longitudinal axis of shaft 27, which is the axis of revolution of the shaft, would remain fixed in space and be concentric with axis 36. Under these conditions, the motion of lower grinding element 21 would be purely a rotational one and entirely conventional in every respect. However, there has been added to this rotational motion an oscillatory motion so that the actual motion of the lower grinding element is a resultant of these two motions.

The oscillatory motion is introduced by the fact that bore 31 is eccentric with respect to the axis of revolution of sleeve 33 as established by bearings 34 and 35, this latter axis being axis 36 and concentric with the axis of drive pulley 40. The eccentricity may be seen in Fig. 3 at 27a, and is normally of the general magnitude of $\frac{1}{8}$ ", but may be more or less as desired. As drive pulley 40 turns, it carries with it plate 53 and bearing pins 57. The relative movement of the bearing pins with respect to stationary ring gear 52 causes large pinions 55 to rotate about pins 57. Small pinions 54 rotate at the same speed as pinions 55, but having a smaller number of teeth they cause ring gear 51 to be rotated in the opposite direction to shaft 27 and at a considerably lower speed. The absolute speed of sleeve 33 may be less than 0.1 the speed of the drive shaft so that the moving stone 21 oscillates across the stationary stone at a relatively low speed. Typically, if the drive pulley is turning at 1200 R. P. M. sleeve 33 is revolved at 100 R. P. M. or thereabouts.

Rotating sleeve 33 carries with it the eccentrically mounted bushing 30 and bearing 29, causing axis 28 to move positively over a definite path. Since axis 28 passes through fixed point 44, to intersect axis 36, axis 28 is normally canted or deflected slightly with respect to axis 36, as shown in Fig. 1. Bearing 29 is likewise canted slightly; but, viewed endwise axially of axis 36, it moves in a circular path lying in a plane normal to axis 36, and substantially so with respect to axis 28. Thus at any transverse cross section, shaft 27 may be considered as having a circular movement about axis 36 in a plane generally perpendicular to the longitudinal axis of the shaft. The radius of the circle of motion at bearing 29 equals the eccentricity 27a referred to above.

From these considerations it is obvious that axis 28 follows a conical path with its apex at

44; and viewed from the side oscillates between the positions 28 and 28a of Fig. 1. The shaft is positively deflected from alignment with the axis of pulley 40 by movement of bearing 29, this deflection being permitted by the spherical conformation of the lower end of drive shaft 27 in thrust bearing 42. This oscillating movement of shaft 27, causes lower grinding element 21 to oscillate from side to side across stone 20 with the result that no point on the moving stone continuously retraces the same path over the stationary stone.

Drive shaft 27 is mounted near both ends in bushings which comprise flexible or elastic sections. These bushing sections are preferably made of rubber so that they act as shock absorbers to take up shock or vibrations resulting from imperfect dynamic balance of the rotor assembly. By interposing these elastic members in the bearing assembly, the main bearings are protected against excessive wear and their life is greatly extended.

From the foregoing it will be apparent that the fine grinding may be accompanied by more or less crushing action, or that crushing may be a major part of the action of the elements 20 and 21. I refer to them as grinding elements; but do so with the understanding that I am not limiting my invention by so doing to any specific type of grinding or crushing action between surfaces 23.

Having described a preferred embodiment of my invention and certain modifications thereof, it will be understood that various changes may be made in the design and construction of a grinder of the character described without departing from the spirit and scope of my invention; and consequently I wish the foregoing description to be considered as illustrative of, rather than limitative upon, the appended claims.

I claim:

1. In grinding apparatus, the combination comprising: a pair of cooperating grinding elements having spherically contoured coacting grinding surfaces, one of said elements being rotatable; a shaft rotatably mounted and carrying at one end said rotatable grinding element, the other end of said shaft being held in a resilient mounting permitting limited movement of said shaft about the center of said spherically contoured surfaces; means for moving the longitudinal axis of the shaft in a path which is circular in a plane generally perpendicular to the longitudinal axis of said shaft; means for moving the other of said grinding elements toward or away from the rotatable element to adjust the grinding clearance between the two elements, said means comprising a pair of loosely threadedly interengaging members capable of limited non-rotational axial movement relative to each other, one of which carries the stationary grinding element and is held against rotation while the other is held against translation, and means for rotating said other member to move the one member toward or away from the rotatable grinding element; and means for applying fluid pressure to the translatable one of the interengaging members to establish a predetermined grinding pressure at the grinding surface.

2. In grinding apparatus including a pair of cooperating grinding elements having coacting grinding surfaces of which one element is stationary and the other element is rotatable, means for adjusting the grinding clearance between the

11

two elements, comprising: a pair of loosely threadedly interengaging members capable of limited non-rotational axial movement relative to each other, one of which carries the stationary grinding element and is held against rotation and the other of said interengaging members is held against translation; means for rotating said other one of the interengaging members a predetermined amount to move said one member toward or away from the rotatable grinding element; and means for applying fluid pressure to the translatable one of the interengaging members to establish a predetermined grinding pressure at the grinding surfaces.

3. In grinding apparatus, the combination comprising: a pair of cooperating grinding elements having spherically contoured coacting grinding surfaces, one of said elements being rotatable; a shaft rotatably mounted and carrying at the upper end said rotatable grinding element; driving pulley means mounted to rotate about a fixed axis; a concentric thrust bearing carried on the drive pulley to rotate therewith and engaging the lower end of the shaft to resist axial thrust on the shaft, the bearing permitting rocking movement of the shaft relative thereto; a resilient driving member connected to the drive pulley means and to the shaft to transmit power for rotating the shaft, the resilient member permitting limited deflection of the shaft axis from the pulley axis; and secondary drive means engaging the shaft intermediate its ends to move the rotatable grinding element in a path around the pulley axis.

4. Grinding apparatus as in claim 3 which also includes a planetary gear train drivingly interconnecting the drive pulley means and the secondary drive means.

10

5. Grinding apparatus as in claim 3 in which the secondary drive means includes a rotatable sleeve; a bearing for the shaft mounted on the sleeve eccentrically with respect to the axis of rotation of the sleeve; and a resilient driving member interposed between the last mentioned bearing and the sleeve to permit the bearing to tilt with respect to the sleeve as the bearing is moved through a path around the pulley axis.

HARDING F. BAKEWELL.

12

5. Grinding apparatus as in claim 3 in which the secondary drive means includes a rotatable sleeve; a bearing for the shaft mounted on the sleeve eccentrically with respect to the axis of rotation of the sleeve; and a resilient driving member interposed between the last mentioned bearing and the sleeve to permit the bearing to tilt with respect to the sleeve as the bearing is moved through a path around the pulley axis.

HARDING F. BAKEWELL.
